Attorney

UNITED STATES PATENT OFFICE.

ALFRED L. COBB, OF LONG BEACH, CALIFORNIA.

TRUSS PAD.

Application filed November 12, 1923. Serial No. 674,350.

To all whom it may concern:

Be it known that I, ALFRED L. COBB, a citizen of the United States, residing at Long Beach, in the county of Los Angeles and State of California, have invented a new and useful Truss Pad, of which the following is a specification.

The present invention has reference to truss construction, and more particularly 10 the pad thereof.

The primary object of the invention is to provide means for securing a pad to its supporting rod in a manner to permit of unrestricted adjustment of the pad so that 15 the user may adjust the pad for a better application of the pad.

Another important object of the invention is to provide a pad which may be secured in its position of adjustment, eliminating 20 any possibility of the pad getting out of adjustment under ordinary conditions.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made 30 within the scope of what is claimed, without departing from the spirit of the invention.

Referring to the drawing:

Figure 1 is a rear elevational view disclosing a pad constructed in accordance with the invention as secured to its supporting rod.

Figure 2 is a side elevational view thereof.

Figure 3 is a sectional view taken on line 40 3-3 of Figure 1.

Figure 4 is a sectional view taken on line 4-4 of Figure 1.

Referring to the drawing in detail, the reference character 5 designates a supporting rod to which the usual cloth material forming the straps of the truss, is secured.

The pad includes preferably a solid body portion indicated at 6, curved in the usual and well known manner so that the same 50 will properly fit the body of the user.

Secured to the flat or rear surface of the pad body, is a plate indicated at 7 which has curved ends conforming to the curva-

ture of the pad structure, the central portion of the plate being curved and offset 55 at 8, to accommodate the rod 5, it being understood that the curvature of the offset portion 8 conforms to the curvature of the rod 5 to closely grip the rod 5.

The body portion 6 is also formed with a 60 groove indicated at 9, which groove is disposed under the offset portions 8 of the plate 7 to accommodate the rod 5, permitting the rod to move with respect to the pad, or vice versa, but at the same time restricting movement of the pad longitudinally of the rod 5.

A cut out portion 10 is formed in the pad and accommodates the sleeve 11 fitted over the rod 5, the ends of the sleeve being 70 designed to engage the end walls of the cut out portion 10 to further restrict longitudinal movement of the pad with respect to its supporting rod. Extending through a threaded opening formed in the sleeve 11 75 is a set screw 12, adapted to engage the supporting rod associated therewith to secure the sleeve in various positions of adjustment to insure against the pad slipping longitudinally of its supporting rod. 80

The plate 7 is formed with a central cut out portion 14 providing a clearance for the sleeve, the width of the cut out portion 14 being greater than the width of the tubular member to allow of movement of the 85 pad, in a rotary plane with respect to the rod. As shown, the screw 12 is of a length to contact with the plate 7, when the plate moves to adjust itself, thereby restricting movement of the body portion with respect 90 to the rod 5.

Screws 13 secure the plate 7 to the body portion of the pad and insure the plate being properly held against accidental displacement. From the foregoing it will be 95 obvious that due to the construction as shown and described, the pad or body portion 6 is free to adjust itself to various movements of the body of the user, but at the same time be restricted from movement 100 longitudinally of the supporting rod.

I claim:—

A truss pad including a body portion, said body portion having a groove extending transversely thereof throughout the width 105 of the body portion, a plate having a cen-

tral offset portion overlying the groove, said plate having a central cut out portion, a supporting rod adjustably mounted in the groove, a collar mounted on the rod and disposed in the cut out portion, and adjustable means for securing the collar in position, and said collar adapted to limit the

longitudinal and rotational movement of the pad with respect to the supporting rod.

In testimony that I claim the foregoing 10 as my own, I have hereto affixed my signature.

ALFRED L. COBB.
